UNITED STATES PATENT OFFICE.

BYRON O. JONES, OF CHICAGO, ILLINOIS.

PIANO-STOOL.

1,142,174.

Specification of Letters Patent.

Patented June 8, 1915.

Application filed October 14, 1912. Serial No. 725,605.

To all whom it may concern:

Be it known that I, BYRON O. JONES, a citizen of the United States, residing at Chicago, in the county of Cook and State of Illinois, have invented a certain new and useful Improvement in Piano-Stools, of which the following is a specification.

This invention relates to piano stools and has for its object to provide a new and improved device of this description.

My invention has among other objects to provide a seating device such for example as a piano stool which can be adjusted for use in playing the ordinary piano and in playing a piano player. When playing the ordinary piano, the stool seat or top should be flat. When playing the piano player, the operator is required to operate the bellows with his feet and it is very important that the seat be so arranged as to facilitate this. By making the seat or top inclined so that the portion nearer the piano is higher than the other portion, the operator is given a purchase on the seat so that he can easily and efficiently operate the bellows of the piano player.

The invention is illustrated in the accompanying drawings, wherein—

Figure 1 is a view showing one form of stool embodying the invention; Fig. 2 is an enlarged view showing the connection between the stool seat and base; Fig. 3 is a sectional view taken on line 3—3 of Fig. 2; Fig. 4 is a sectional view taken on line 4—4 of Fig. 3.

Like numerals refer to like parts throughout the several figures.

For purpose of illustration, I have shown my invention as applied to a piano stool having a circular top. As herein illustrated, the top 1 of the stool is rotatably connected with the base 2 so that it can be easily turned, and is preferably arranged so that it can be raised and lowered by turning in the ordinary way. Means is provided for easily and quickly inclining this top and holding it in this inclined position when desired. In the construction shown, the top 1 is provided with a projection 3. This projection is pivotally connected with a support. This support has two projecting parts 4 and 5, connected with the supporting piece 6, which in turn is connected with the base 2. The projection 3 passes between the two projecting parts 4 and 5 and is pivotally connected with the parts 4 and 5 in some suitable manner as

by means of a pin 7. The projection 3 is provided with an eccentric hole or opening 7^a. Located within this opening is an eccentric 8 connected with a rotatable piece 9 mounted in the parts 4 and 5. The piece 9 is provided with a handle 10 so that it can be given a partial rotation. When the parts are in position as shown in Fig. 2, the top of the stool is flat, the stool being in proper condition to be used in playing the piano. When it is desired to operate the piano player, the operator takes hold of the handle 10 and moves it to the position shown in dotted lines in Fig. 1. This causes the eccentric 8 to be rotated in the enlarged opening 7^a, thereby causing the projection 3 to be moved to the position shown in Fig. 4. When in this position, the top 1 is inclined as shown in dotted lines in Fig. 1 so that the device is in position to use the piano player. The high edge of the top 1 is placed toward the piano player thus giving the user a purchase on the seat so that such user can operate the bellows easily and efficiently. The top 1 is locked in this inclined or tilted position by means of the cam as the pressure of the projection 3 on the cam is applied thereto so that the cam can not be rotated by this pressure. I prefer to arrange the axis of rotation of the cam and the part 9 so that it will be on one side of the center of the pin 7. When it is desired to use the device in playing the ordinary piano, the handle 10 is moved back to the position shown in full lines in Fig. 1 which moves the top back to the flat or level position, the top being held rigidly in this position by the cam. The opening 7^a is elongated longitudinally. It is of such width that the cam engages the sides thereof in all the various positions of the cam so that there will be no lost motion, and so that the full effect of the cam will be utilized in tilting the top.

I claim:

1. A piano stool comprising a top and a base, a single central standard connecting the top and base, a movable connection in said central standard between the top and the base whereby the top may be moved to an inclined position, and means contained in said central standard for locking the top in said inclined position.

2. A seating device comprising a top, a base therefor, a central connection between the top and base comprising over-lapping parts on the top and base, a piece passing

through said overlapping parts by means of which they are pivotally connected together, a second piece passing through said overlapping parts, said second piece located below the first mentioned piece, an eccentric connected with said second piece and acting as an actuating device to move said top when the second piece is rotated and as a lock to hold said top in any of its various positions.

10 3. A seating device comprising a top and a base, a pivotal connection between said top and said base, a rotatable part mounted upon said base, an eccentric forming a part 15 of said rotatable part and engaging the part connected with said top, said eccentric adapted when rotated to move the top in an inclined position.

4. A seating device comprising a top, a projection connected therewith near the middle thereof, a supporting piece for said top, a pivotal connection between said projection and said supporting piece, a rotatable part mounted upon said supporting piece, an eccentric connected with said rotatable part engaging said projection on the top, said eccentric adapted when rotated to move the top to an inclined position.

5. A seating device comprising a top, a 30 supporting projection connected therewith, a supporting piece for said top, a pivotal connection between said supporting projection and said supporting piece, a rotatable part mounted upon said supporting piece, a cam connected with said rotatable part engaging said supporting projection on the top, a handle connected with said rotatable part and adapted when moved to one position to move the top to an inclined position, 35 and when moved to another position to move said top to its flat position.

6. A seating device comprising a top, a supporting projection connected therewith, a supporting piece for said top, a pivotal 45 connection between said supporting pro-

jection and said supporting piece, a rotatable part mounted upon said supporting piece, a cam connected with said rotatable part engaging said supporting projection on the top, said cam adapted when rotated to move the top to an inclined position, the cam and pivotal connection substantially in vertical alinement, the axis of rotation of said cam being located at one side of the axis of rotation of the top about its pivotal connection with the support.

7. A piano stool comprising a top and a base, a central connection between the top and the base comprising over-lapping projecting parts on the top and base, two connections between said over-lapping parts, one a pivotal connection and the other a cam connection.

8. A piano stool comprising a top and a base, a central connection between the top and the base comprising over-lapping projecting parts on the top and base, a pivotal connection between said over-lapping parts, a rotatable part passing through said projections, said rotatable part having a cam which engages one of said projections, whereby when the cam is rotated the inclination of the top will be varied.

9. A piano stool comprising a top and a base, a central connection between the top and the base comprising over-lapping projecting parts on the top and base, a pin passing through said projections, a second pin also passing through said projections, said second pin having three parts of different diameters, one of said parts being cam shaped.

In testimony whereof, I affix my signature in the presence of two witnesses this 11th day of October, 1912.

BYRON O. JONES.
